UNITED STATES PATENT OFFICE.

WILLIAM H. BAKER, OF MONTREAL, QUEBEC, CANADA.

FUSIBLE LINK.

Application filed December 19, 1919. Serial No. 346,003.

To all whom it may concern:

Be it known that I, WILLIAM H. BAKER, a citizen of the United States, and resident of the city of Montreal, in the Province of Quebec and Dominion of Canada, have invented certain new and useful Improvements in Fusible Links, of which the following is a full, clear, and exact description.

This invention relates to improvements in fusible links such as are used in sprinkler heads and the like, and the object of the invention is to provide a link which may be cheaply and easily manufactured and durable and efficient in operation.

15 A further object is to provide a link so constructed that upon elongating movement, the link parts will simultaneously move away from one another in the flatwise direction.

20 A still further object is to provide a two-part link.

The device consists briefly of a pair of similar plates, each having an integral tongue lying at an inclination to the plate surface and adapted to slidably support a 25 corresponding tongue of the other plate.

In the drawings which illustrate the invention;—

Fig. 1 is a plan view of a link formed according to this invention.

30 Fig. 2 is a longitudinal central section of the link.

Referring more particularly to the drawings, 11 and 12 designate a pair of similar plates each having toward one end an attachment aperture 13 and at the opposite end a notch 14 adapted to expose the aperture of the other plate.

Each link is provided with a centrally disposed aperture 15, the metal removed 40 from the aperture being allowed to remain integral with the plate in the form of a tongue 16. This tongue is bent outwardly from the plate and then bent upon itself at 17, so as to provide a portion 18 projecting through the aperture 15. These tongue parts 18 are arranged in planes extending transversely of the plates and out of normal with the plane of the plate. As shown, in 45 Figure 2, the plane of each tongue part 18 is at an angle of approximately sixty degrees to the plane of the plate, but it will be understood that the invention is not confined to this or to any specific angle within the range of practicability. The plates are 50 assembled as shown in Figure 2 with the tongue tip of each plate projecting through

the opening 15 of the other plate and the tongue tips in sliding contact with one another. The plates are then connected in the usual manner by solder of any desired 60 temperature. For the purposes of clear illustration the solder has been omitted from the drawing, as its disposition is so well known in the art.

The bend 17 in each tongue should have 65 sufficiently large radius, so that the metal of the tongue will not be cracked or in any way weakened by the bending and at the same time the radius must be sufficiently short, so that the tendency to spring is practically nil 70 under the load to which the link is subjected. In order to obtain requisite strength and stiffness, it is advisable to keep the portion of the tongue between its root and the bend 17 as nearly in the plane of the plate as 75 possible having regard to proper bearing surface between the tongues when the link is assembled. The angle between the plane of the tongue parts 18 and the plate should be such that there will be considerable sliding tendency between the tongues when the link is assembled and in tension. This sliding tendency must not, however, be greater than the strength of the solder will resist for an indefinite period. On the other hand, 80 the plane of the tongues must not be so nearly perpendicular to the plane of the plates that there will be any marked resistance to the sliding action of the tongues.

85 The operation of the device is extremely 90 simple. When the link is in tension the inclined tongue tip 18 of one plate is drawn toward the inclined tongue tip of the other plate. Owing to the inclination of these 95 tips, they have a tendency to slide in opposite directions and thus force the plates flatwise apart. Normally, this separating action is resisted by the solder connecting the plates but, when the link is heated to a predetermined temperature, the solder softens 100 and the tension on the link becomes effective to produce sliding movement between the tongues and complete separation of the plates. The flatwise separation of the plates produces an instantaneous break or opening 105 of the link and precludes any possibility of the link elongating slightly by a wiping or sliding movement and then becoming chilled. The inclined tongues not only produce the desired plate separation but also relieve the 110 solder connecting the plates of practically all shearing stress.

The link illustrated is designed to withstand tension, but it will be understood that the invention includes the obvious modification necessary to constitute a compression link. It will also be understood that while the link plates are illustrated and described as formed of stamped sheet metal that they may be formed by casting or die pressing with equal facility, in which case the tongues 10 will in all probability be solid.

Having thus described my invention, what I claim is:—

1. In a device of the class described, a pair of apertured plates each having a tongue 15 projecting through the aperture of the other plate and into sliding contact with the other tongue.

2. A device of the class described comprising a pair of plates, a tongue struck 20 from each plate and forming an aperture in

the plate, said tongue being first bent away from the plate and then upon itself to pass through the aperture of the plate carrying it and into the aperture of the other plate, said tongues being disposed at an angle other 25 than 90 degrees to the plate surface and arranged in sliding engagement with one another.

3. In a device of the class described, a pair of apertured plates in sliding contact with 30 one another, each of said plates carrying a tongue projecting through the aperture of the other plate, said tongues being in engagement and inclined in the engaging portions, said engaging portions being disposed symmetrically on opposite sides of the plane of 35 contact of the plates.

In witness whereof, I have hereunto set my hand.

WILLIAM H. BAKER.
